UNITED STATES PATENT OFFICE.

EDWARD G. DURANT, OF RACINE, WISCONSIN, ASSIGNOR OF ONE-HALF TO
THOMAS KANE, OF CHICAGO, ILLINOIS.

OPERA-CHAIR.

SPECIFICATION forming part of Letters Patent No. 323,301, dated July 28, 1885.

Application filed September 8, 1884. (No model.)

To all whom it may concern:

Be it known that I, EDWARD G. DURANT, of Racine, in the county of Racine and State of Wisconsin, have invented certain Improvements in Opera-Chairs, of which the following is a specification.

The present invention relates to that class of folding seats commonly denominated "opera-chairs," in which the seat and back are pivoted to swing in a vertical direction and connected with each other in such manner that the act of folding the seat upward will cause the back to assume a vertical position to afford increased room for the ingress and egress of the audience.

The aim of the invention is to cheapen, simplify, and reduce the size of the connections between the seat and back, and also to adapt the connecting devices for use upon standards located between adjacent seats to support the edges of both.

With these ends in view the invention consists in the peculiar arrangement and construction of parts, hereinafter described and claimed.

Referring to the accompanying drawings, Figure 1 represents a front elevation of a series of chairs constructed on my plan, the middle chair being shown in a folded position. Fig. 2 is a perspective view of this portion of the standard and the connecting-arms for giving support to the inner edge of the seat and back. Fig. 3 is a side elevation of the parts represented in the foregoing figure, with retaining-plate removed, the parts being in position for use. Fig. 4 is a like view of the parts as they appear when the chair is folded. Fig. 5 is a horizontal section on the line xx of Fig. 3. Fig. 6 is a vertical section on the line yy of Fig. 5. Fig. 7 is a side elevation 40 of the middle part of one of the standards.

Referring to the drawings, A A represent rigid upright standards bolted or otherwise secured to the floor, and which may have any form or configuration desired, except as to the details of the active surfaces, hereinafter explained. Each standard is provided on its side face with two horizontally-projecting trunnions, a and b , and with cavities or recesses c , located adjacent to the trunnions, as shown, 45 to afford shoulders to interlock with the arms

for supporting the seat and back. When the arms are designed, as usual, to give support to the adjoining seats, they are provided with trunnions and recesses on both sides, as shown in Fig. 5; but those standards which are to be located at the end of the row, or to be used in connection with a single seat, may have one side left plain or without trunnions.

B B represent the back-supporting arms, the lower ends of which are provided with 60 sockets to receive the trunnions a , and with studs d to enter the recesses c in the standard. The studs serve, as usual in this class of furniture, to engage the shoulders of the standard and give support to the arms and the back of 65 the chair when in use. The upper ends of the back-arms are flanged, as shown, or otherwise adapted for attachment to the edge of the back. As shown in Figs. 1 and 2, the arms are curved inward away from the standard, or, in other 70 words, toward the back, in order that the edge of the back may be supported at such distance from the standard as to admit of its swinging past the arm-rest or other projecting portion of the standard.

C C represent the seat-supporting arms, the rear ends of which are recessed to fit upon the trunnions b , and provided with studs d , to enter the corresponding recesses in the standard, so that when the seat is in use the supporting-arms C will be sustained wholly by means of the trunnions and studs.

Each of the back-arms is provided with an arm or ear, e , extending downward below the pivot, and provided with a small hole near 85 its extremity. Each of the seat-arms is provided with a small hole in rear of the journal. The distance from this hole to the center of the seat-arm is much less than the distance from the hole in the back-arm to its center. 90 The two arms are connected by means of a link, D, having lateral projections or journals at its ends. These journals are seated one in the hole in the seat-arm and the other in the hole in the back-arm, as plainly represented in Figs. 3 and 95 4. By means of this connection the swinging motion of either arm will cause a like motion to be imparted to its companion, whereby the two are caused to assume a vertical or an operative position simultaneously. Owing to the 100

fact that the link is connected at a greater distance from the center of the back-arm than from the center of the seat-arm, the latter is permitted to swing through an arc much greater than that of the back-arm, as is required in consequence of the fact that the back has but a slight inclination from the vertical when in use.

As a means of retaining the link in connection with the arms and of retaining the arms in position upon the trunnions, as well as to apply a friction sufficient to prevent the seat from falling in a noisy manner, I employ a pressure-plate, E, the outside ends of which bear upon the inner side of the two arms. This plate is secured in place by means of a central bolt, F, passed through it and through the standard between the arms, as shown in the drawings. In order to apply a yielding pressure to the plate, I place around one end of the same an elastic metal disk, p, which bears at its edges only in a cavity formed in the outer side of my pressure-plate E. The bolt being tightened by means of a nut on its end subjects the plate to a strain or tension, causing it to force the plate against the arms with a yielding pressure.

When a single standard is employed between the two seats, it will be provided with a seat-arm and a back-arm on each side, as shown in Fig. 5, and with a pressure-plate for each pair of arms. In such case the bolt F will be extended not only through the standard, but also outward through both pressure-plates, as shown in Fig. 5.

I am aware that in a seat supported at the center by a single upright standard a back-arm and a seat-arm have been connected by a link arranged on the outer sides of the arms, as in the patent to Bailey and Schade, No. 264,216, the construction being such as to prevent the use of a single standard to support two adjoining chairs.

I am also aware that a back pivoted midway of its height has been connected at its lower end by a long link to a seat having its journals arranged to slide forward and backward in horizontal slots in a standard, as in the patent to Koechling, No. 155,452, and to such construction I lay no claim.

It is to be observed that in my structure the arms and the link by which they are connected are arranged on the inner face of the supporting-standard between the standard and the side of the seat. This is a feature of special importance, in that it permits the use of the standard to support two seats, as before explained.

It is to be noted as another peculiarity of my construction that the connecting-link extends from a point on the back-arm below its pivot to a point on the seat-arm in rear of its pivot. This construction permits the use of a link shorter, if desired, than the distance between the pivots of the two arms, so that it may be seated compactly and closely between

the edges of the arms, as represented in the drawings. This is highly advantageous in that it permits the ends of the arms to be made of small size and the entire joint to be brought within a small compass, so that it may be used on a very narrow standard. The result is a chair which, when folded, occupies very little space from front to rear, thus affording wide spaces or passages between the chairs of one row and those of the next, and permitting an increased number of chairs to be advantageously placed on a floor of given size.

In the particular arrangement of the link herein described my construction differs widely from the links represented in the Koechling patent, which are required to extend past and in advance of the pivot of the chair-seat, and which, because of their necessarily great length, render indispensable the use of an exceedingly wide standard.

I do not claim herein the construction represented in the patents granted to Durant and Shupe, February 19, 1884, No. 293,724, or to Durant and Kane, March 27, 1883, No. 274,742, or either of them. The construction herein shown and claimed is advantageous in that there are in the connection between the arms no sliding joints and no surfaces requiring to be accurately fitted.

Having thus described my invention, what I claim is—

1. In an opera-chair, the combination, substantially as hereinbefore set forth, of the standard, the back-arm and seat-arm connected thereto by fixed journals, and the connecting-link jointed to the back-arm at a point below its journals, and to the seat-arm at a point in rear of its journals, substantially as described and shown, whereby the use of a short link is permitted and a compact joint is produced.

2. The combination, substantially as described and shown, of the standard having the fixed journals thereon at the same or substantially the same height, the back-arm mounted on one of said journals and extended below the same, the seat-arm mounted on the other journal, and the link pivoted at one end to the seat-arm in rear of its journal, and at the opposite end to the lower extremity of the back-arm, whereby the two arms are caused to move in unison and the employment of a short link permitted.

3. The combination of the standard, the back-arm journaled thereon and extended below its journal, the seat-arm, also pivoted to the standard, and the connecting-link pivoted at one end to the seat-arm, and at the opposite end to the lower extremity of the back-arm, as and for the purpose described.

4. In an opera-chair, the combination of a rigid standard, the back-arm and seat-arm journaled to said standard on the inner side or side next to the seat proper, and the link connecting said arms, and located also on the inner side of the standard, whereby the outer

side of said standard is rendered available to support the arms of a second seat when required.

5. In combination with the standard provided with journals or trunnions, the back and seat arms mounted upon said trunnions, the link D, having its ends connected by journals to the respective arms, the plate E, and means, substantially as described, for securing said plate against the link and arms, whereby the plate is caused to serve the double purpose of retaining the arms in position upon the trunnions and of maintaining the connection between the arms and the link.

15. 6. The combination of the standard, the two arms pivoted on one side thereof, the plate bearing on the two arms and provided with a central concavity, the elastic disk seated in

said cavity and bearing at the edge only, and the central bolt, applied as shown. 20

7. The combination of the standard having two pairs of journals formed on opposite sides thereof, a back-arm and a seat-arm mounted on each side of said standard, the links connecting the back and seat arms in the manner 25 described and located against their inner faces, whereby a single standard is adapted to sustain the adjacent edges of two seats, and the two arms of each seat adapted to operate simultaneously and independently of those on 30 the other seat.

EDWARD G. DURANT.
